J. G. Kennedy,
Attorney.

UNITED STATES PATENT OFFICE.

RAY W. FRANKLIN, OF MONTICELLO, IOWA, ASSIGNOR TO FRANKLIN BARN EQUIPMENT COMPANY, OF MONTICELLO, IOWA, A CORPORATION OF MAINE.

CONNECTING DEVICE.

1,301,417.

Specification of Letters Patent. Patented Apr. 22, 1919.

Application filed April 6, 1918. Serial No. 227,148.

To all whom it may concern:

Be it known that I, RAY W. FRANKLIN, a citizen of the United States of America, and a resident of Monticello, Jones county, 5 Iowa, have invented certain new and useful Improvements in Connecting Devices, of which the following is a specification.

My invention relates to improvements in connecting devices, and the object of my 10 improvement is to supply a rigid securing means for elements positioned angularly to each other, which will permit relative play in one direction to one element, while resisting stresses acting thereon in other directions.

This object I have accomplished by the means which are hereinafter described and claimed, and which are illustrated in the accompanying drawings, in which Figure 1 20 is an elevation of a swinging gate whose frame includes a plurality of my improved connecting devices, a part of one gate-stile being broken away; Fig. 2 is a side elevation on a larger scale of one of said connecting devices; Fig. 3 is a cross-section thereof, and Fig. 4 is a plan view thereof.

Similar numerals of reference denote corresponding parts throughout the several views.

30 In Fig. 1 is shown a flexible gate whose rear stile 1 is hinged at 10 to a rear post 9. Both the rear stile 1 and the front stile 8 are formed of U-bars, which are connected together pivotally at tops and bottoms by 35 means of horizontal pipes or tubes 7. The stiles are also connected by means of netted wire, while a wire 11 leads from one end of the rear stile 1 diagonally across the length of the gate to a clip 12 slidably adjustably 40 mounted about the front stile 8, whereby the frame parts of the gate may be flexed in a well-known manner to raise or lower its forward free end.

Referring now to the other figures, the 45 numeral 2 denotes a sleeve fixedly mounted on a tube 7 near one end thereof by means of a rivet 3. This sleeve has forks 4 which span the U-bar stile 1, contacting the opposite outer faces thereof. It will be observed

that both the sleeve 2 and its forks 4 are 50 set back from the extremity of the tube 7, said extremity passing between the opposed inner walls of said stile as far as possible and contacting therewith. Orifices are supplied in said forks, stile and tube extremity 55 to receive a pivot-bolt 5, which is tightly secured by means of a nut 6, the orifices 13 in said forks 4 being elongated longitudinally to permit adjustments thereof relative to the stile when necessary.

It will be seen that the tube 7 may swing 60 in one direction on the pivot-bolt 5. The elements of the connection, however, are so assembled and associated as to make a very strong and rigid joint, such as will best resist torsional strains without breaking or 65 distorting any element thereof, as might occur with a long heavy gate whose tube parts 7 exert considerable leverage. As will be best seen in said Fig. 4, the extremity of 70 the tube 7 has a relatively long contact with the inner walls of the U-bar 1, thus affording an additional grip and reinforcement besides the clamping engagement of the forks 4 with the outer walls of the U-bar. 75 The whole thickness of the tube 7 is therefore made available as a reinforcement of the joint, which relieves the forks 4 of most of the strain, besides giving said tube an additional pivotal bearing on the pivot-bolt 5.

While my improved connecting device is 80 illustrated in use in connecting the frame elements of a gate, it is obvious that it may be employed to connect any two bodies together without departing from the principle 85 of my invention.

Having described my invention, what I 90 claim as new, and desire to secure by Letters Patent, is:

In combination, a body having an opening, a beam having one extremity mounted within the opening of said body to engage its opposite inner walls, a sleeve fixedly mounted on said beam and having forks 95 spanning and engaging opposite outer faces of said body, all said parts being orificed in line, the orifices in said forks being slo-

gated longitudinally, a pivot-bolt seated in said alined orifices, and securing-means adjustably mounted on said pivot-bolt to secure said parts together in engagement while 5 permitting swinging movements in one plane only to said beam relative to said body.

Signed at Monticello, Iowa, this 25th day of March, 1918.

RAY W. FRANKLIN.
